UNITED STATES PATENT OFFICE.

TOMAS FRED HOUSE, OF HURST, MISSOURI.

HAY-STACKER.

1,104,671.

Specification of Letters Patent.

Patented July 21, 1914.

Application filed December 29, 1913. Serial No. 809,414.

To all whom it may concern:

Be it known that I, TOMAS FRED HOUSE, a citizen of the United States, residing at Hurst, in the county of Texas and State of Missouri, have invented certain new and useful Improvements in Hay-Stackers; and I do declare the following to be a full, clear, and exact description of the invention, such as will enable others skilled in the art to 10 which it appertains to make and use the same.

This invention relates to improvements in hay stackers and more particularly to those employing a stacking head or fork 15 and means for raising said fork to an upright position.

The primary object of the invention is to provide a stacker of this type with improved means for imparting a return movement to the stacker head after the same 20 has been raised to an upright position.

A secondary object is to provide means for applying a braking action to the supporting wheels of the stacker simultaneously 25 with imparting the above mentioned return movement to the stacking head.

With the above objects in view, the invention resides in certain novel features of construction and combination herein described 30 and claimed and shown in the accompanying drawings wherein:

Figure 1 is a side elevation of my improved stacker; Fig. 2 is a plan view thereof; and Fig. 3 is a detail vertical section on the line 3—3 of Fig. 1.

In the embodiment illustrated, the stacker comprises in general, a supporting frame 1, arms 2 pivoted to one end thereof, a stacking head or fork 3 carried by the outer ends 40 of said arms, an A-shaped hoisting frame 4, a cross head 5 carried by said A-frame, connections 6 between one end of said cross head and said arms 2, a block and tackle mechanism 7 for actuating said hoisting frame, and flexible cables 8 connected to the fork 3 at one end and having yielding connections with the frame 1 at their opposite ends.

Coming now more particularly to details 50 of the present invention and parts closely coacting therewith, the supporting frame 1 comprises longitudinal side bars 9 connected at their opposite ends by transverse bars 10, said side bars 9 being provided with openings in which a supporting shaft 11 is rigidly secured.

The lower ends of the side bars 12 forming the A frame, are provided with openings through which the shaft 11 is extended thus pivoting said A frame on said supporting shaft. Disposed on said shaft 11 and spaced a slight distance from the ends of the bars 12 are fixed stops 13 against the inner ends of which bear the outer ends of the hubs of supporting wheels 14. Normally out of contact with the inner ends of said hubs, are sleeves 15 slidably mounted on the shaft 11 said sleeves being provided with guide pulleys 16. Coiled springs 17 encircle the shaft 11 between the sleeves 15 and bear at their opposite ends on the sleeves 15 and within socketed slides 18 mounted on the shaft 11 near its center.

The socketed slides 18 above referred to, are provided with lateral ears 19 to which 75 are fastened the inner ends of chains 20 which lead from said ears under the guide pulleys 16 and are then connected at a suitable point to the flexible cables 8, said cables extending forwardly and being secured to 80 the opposite ends of one of the supporting bars 21 of the fingers 22 forming the tines of the fork.

In the operation of the device, when hay has been loaded onto the stacking head or 85 fork 3, the block and tackle mechanism 7 may be actuated in any suitable way to rock the A-frame 4 around the shaft 11 and by this operation the arms 2 of the fork 3 will be swung around their pivots 2' until 90 they assume a position past a point directly above said pivots. By the time the stacking head has reached this position, the cables 8 will have drawn the chains 19 through the guide pulleys 16 thus compressing 95 the springs 17, the force of which is now exerted to return the stacking head to its normal position.

By the disposition of the springs 17 and their coacting parts, it will be clearly seen 100 that when the stacking head is raised, the socketed slides 18 will be moved by the action of the cables 8 and the chains 20, to compress said springs 17 against the sleeves 15 and force said sleeves into frictional contact with the inner end of the hub of the wheel 14 and said hub will then be clamped between the fixed stops 13 and the sleeves 15. I consider this a very important feature of 105 my invention since the momentum of the stacking head 3 in returning to its normal position is imparted to a great extent to the

main supporting frame 1 and if this frame is not rigidly held, it is liable to move upon its supporting wheels 14 but by the above mentioned positioning of parts, any movement on their part is impossible.

Although I have described my invention with considerable minuteness, I do not wish to be limited to details other than those amplified in the appended claims.

10. What I claim as new is:

1. In a hay stacker, the combination with a supporting frame having a transverse shaft, arms pivoted to said supporting frame, a fork carried by said arms, a hoisting frame, means for actuating the same, and a connecting element between said hoisting frame and said pivoted arms, of a coiled spring slidably mounted on said transverse shaft and having one end fixed, a guide carried by the supporting frame, and a flexible connection secured to said fork, passing through said guide, and secured to the free end of said coiled spring.
2. In a hay stacker, the combination with a supporting frame having a transverse shaft, arms pivoted to said supporting frame, a fork carried by said arms, a hoisting frame, means for actuating the same, and a connecting element between said hoisting frame and said pivoted arms, of a fixed stop carried by said transverse shaft, a supporting wheel having its hub journaled on said shaft, and bearing against said stop, a sleeve slidably mounted on said shaft and bearing against the opposite end of said hub, a guide on said sleeve, a spring slidably mounted on

said shaft and bearing at one end against said sleeve, and a flexible connection secured to said fork and the free end of said spring and passing through the guide of said sleeve.

3. In a hay stacker, the combination with a supporting frame having a transverse shaft, a sleeve slideable on said shaft, a guide on said sleeve, arms pivoted to said supporting frame, a fork carried by said arms, a hoisting frame, means for actuating the same, and a connecting element between said hoisting frame and said pivoted arms, a spring loosely coiled around said shaft and bearing at one end against said sleeve, and a flexible connection secured to said fork and the free end of said spring and passing through the guide of said sleeve.

4. In a hay stacker, the combination with a wheel supporting frame and a movable lifting member carried thereby, of a movable braking element normally out of engagement with the supporting wheel of said frame, an operating element carried by said lifting member, and a yielding connection between said operating element and said braking element for imparting a return movement to said lifting member when raised and for simultaneously releasing said braking element.

In testimony whereof I have hereunto set my hand in presence of two subscribing witnesses.

TOMAS FRED HOUSE.
